GAS TUBE CIRCUIT

Herman P. Raab, Jr., and Robert L. Haynes, Indianapolis, Ind., assignors, by mesne assignments, to the United States of America as represented by the Secretary of the Navy

Filed June 20, 1945, Ser. No. 600,480

4 Claims. (Cl. 315—350)

This invention relates to gas tube circuits and has for one of its objects the provision of an improved method of and means for rendering a gas tube circuit unresponsive to microphonic and similar undesired signals due to mechanical shock, while permitting signals possessing desired characteristics to actuate the circuit.

Another object of the invention is the provision of an improved gas tube circuit capable of distinguishing between signals caused by mechanical shock and signals due to other causes.

The invention was conceived in the design of a firing circuit for submarine depth charges and will be described, by way of illustration, in its application to such a circuit. It is therefore a further object of the invention to provide an improved firing circuit highly sensitive to signals of very low intensity caused by a varying magnetic field, but unresponsive to signals due to mechanical shock. It will become apparent, however, from the following description that the invention is of general application, and it is not intended to limit the invention to the illustrative example described.

The objects of the invention are achieved by delaying a firing potential applied for any reason to a gas tube, igniting an auxiliary gas tube in response to mechanical shock, and preventing the first-mentioned tube from firing by a signal derived from the ignition of the auxiliary tube.

The invention together with the aforementioned and other objects and advantages may be better understood from the following description of an embodiment thereof when read in conjunction with the accompanying drawings, in which:

Fig. 1 is a schematic diagram of a circuit embodying the invention,

Fig. 2 is a schematic diagram of a firing circuit for submarine depth charges and including the circuit of Fig. 1,

Fig. 3 is a graph illustrating the form of the signal appearing at point *a* of Fig. 1,

Figs. 4, 5, 6 and 7 are graphs on the same time base showing variations in voltage caused by signals at different points under different conditions of the circuit of Fig. 1, and

Fig. 8 is a view in elevation of a switch used in the circuit of Fig. 1.

The circuit of Fig. 2 is intended to be installed in depth charges which are dropped or projected into water to destroy submarines. During the descent of such a depth charge it may pass close to a submarine without actually hitting it. The circuit is designed to respond to the varying or non-uniform magnetic field in the neighborhood of the submarine and to fire the charge when it is at close range thereby increasing its effectiveness.

Depth charges are not always used singly, but are frequently dropped in defined groups or patterns. Mechanical shock which may be caused, for example, by the

explosion of a nearby depth charge, or by the depth charge hitting bottom, sets up microphonics in the various elements of the circuit, and particularly in the amplifier which forms a part thereof. For each depth charge to perform its allotted task it is necessary to render the device unresponsive to microphonic and similar false signals due to mechanical shock.

The circuit of Fig. 2 includes pick-up coils 10 connected to input terminals 2 and 3. When the depth charge passes through a non-uniform magnetic field, a signal which may have an amplitude of no more than one-half a millivolt and a frequency of one or two cycles per second is induced in the pick-up coils and applied to the input terminals. The comparatively weak, low frequency signal thus produced is converted by an input capacitor C_3 , a chopper schematically indicated at 12, and an input transformer 14 into a series of high frequency pulses which are amplified by a two-stage vacuum tube amplifier comprising tubes V_1 and V_2 to a value sufficient to fire a gas tube V_3 connected in cascade with tubes V_1 and V_2 . A circuit associated with the tube V_3 is arranged to deliver a delayed firing signal to a gas tube V_5 which is provided with an output circuit including a capacitor C_{14} . This capacitor is normally charged to 90 volts, and firing of tube V_5 discharges the capacitor and sends a heavy pulse of current through a detonator 16 which is connected between output terminals 4 and 5, thereby firing the depth charge.

The portion of the circuit of Fig. 2 with which the present invention is more immediately concerned has been redrawn for greater clarity in Fig. 1, and the elements common to both figures have been given the same reference indicia in each figure. Fig. 1 also shows, by way of illustration, the values chosen for the various circuit elements in one practical embodiment of the invention.

The circuit of Fig. 1 includes a third gas tube V_4 , in addition to the tubes V_3 and V_5 already mentioned. The three tubes may be identical and in the embodiment described were of a type known as SA-782-B having the following characteristics:

Filament voltage	volts	1.4
Filament current	amps	.080
Anode supply voltage	volts	90
Critical (firing) grid voltage (with 90 volts on anode)	do	1.5
Voltage drop from anode to filament after ionization	do	Approximately 20

50 A battery 18 or other source of direct current is provided with terminals 20a, 20b, 20c, and 20d connected to the anode, filament and grid of each tube to operate the filament and provide anode and grid bias potentials of 90 volts and -3 volts respectively for each tube. The 55 anode and filamentary cathode of the tube V_3 are connected by a resistor R_{16} and capacitor C_{10} in series with a resistor R_{15} common to the three filament circuits. From the junction point *b* of R_{16} and C_{10} , resistors R_{17} and R_{21} connect to terminal 20a of the battery 18. Similarly the anode-filament circuit of the tube V_4 comprises a series-connected resistor R_{20} and capacitor C_{12} , the three resistors R_{17} , R_{21} and R_{20} and capacitor C_{12} being all connected at point *e*.

60 The capacitor C_{14} in the anode-filament circuit of the tube V_5 has already been mentioned, and from the junction point of this capacitor and the anode of V_5 a resistor R_{23} connects to the high voltage terminal 20a of the battery 18.

65 Resistors R_{14} , R_{19} and R_{22} are connected in the grid circuits of each of the tubes V_3 , V_4 and V_5 respectively, to the terminals 20c and 20d of the battery 18 which

provides in conjunction with the common filament resistor R_{15} a total effective bias of -3.3 volts on each grid.

A capacitor C_{13} has one terminal connected to the grid of the tube V_5 and the other terminal to the common point b between R_{16} and C_{10} . The combination which comprises the three resistors R_{16} , R_{17} and R_{22} and the two capacitors C_{10} and C_{13} constitutes a time-delay network connecting the anode of V_3 to the grid of V_5 .

A voltage divider comprising resistors R_{18} and R_{25} is connected across the terminals $20a$ and $20c$ of battery 18 , and a capacitor C_{11} connects the junction point of these two resistors with the grid of the tube V_4 . A normally closed switch S_2 , shown in Fig. 8, is connected in shunt with the resistor R_{25} . The switch may comprise a firmly mounted contact A and a second contact B mounted on a member D which is shown in Fig. 8 as a leaf spring, but may be constructed in any other appropriate manner to provide spring tension between contacts A and B . An additional mass M may be attached to the contact B . The construction is such that with sufficient acceleration even a microscopic displacement resulting from mechanical shock will open the contacts momentarily. Accurate construction is not essential, as would be the case with a normally open switch.

The operation of the circuit described is as follows: In a steady state condition, the three capacitors C_{10} , C_{12} and C_{14} are each charged to 90 volts from the battery 18 . The charge on the capacitor C_{12} may be regarded as providing the necessary operating anode potential for the tube V_3 . The form of the amplified signal appearing on the grid of V_3 is illustrated in Fig. 3. This signal may be caused by mechanical shock as before related, or may be due to a non-uniform magnetic field relative to the pickup coils 10 caused by the presence of, say, a submarine. When this signal reaches a value of at least -1.5 volts, V_3 fires and C_{10} is discharged through R_{16} and V_3 until the charge is reduced to approximately 30 volts, whereupon V_3 is extinguished and C_{10} is recharged exponentially from the direct current source 18 through R_{21} and R_{17} . Fig. 4 shows how the anode voltage of V_3 varies upon ignition of that tube, while the solid curve of Fig. 5 shows the variation of voltage with time at point b of Fig. 1 which is effectively the terminal of the capacitor C_{10} shown uppermost in that figure.

The voltage variations at point b illustrated in Fig. 5 and caused by firing of V_3 , produce a transient voltage at point d (the grid of V_5). The variations of this transient voltage are shown in Fig. 6. The zero line in Fig. 6 represents the situation before V_3 is fired, and it will be remembered that the grid of V_5 is then biased to -3.3 volts with respect to its cathode. On firing of V_3 the grid voltage of V_5 falls sharply by about 60 volts, and then rises as shown in Fig. 6 until it reaches a point more than 1.8 volts in excess of the steady state condition, whereupon the critical voltage is attained, and V_5 fires. With the circuit elements concerned having the values shown in Fig. 1 the period of delay between firing of V_3 and V_5 is approximately $.025$ second.

Now if the signal which caused firing of V_3 was due to mechanical shock that shock will have caused at least a momentary opening of the switch S_2 . This opening will have been effected instantaneously upon the occurrence of the shock and will have applied a transient voltage pulse to the grid of V_4 . R_{25} and R_{18} are so related in value to each other and to the 90 volt source 18 that this pulse will have a peak value of approximately 8 volts, which is more than sufficient to raise the potential of the grid of V_4 from the -3.3 volts to which it is normally biased to the -1.5 volts necessary to fire it. V_4 therefore fires substantially instantaneously upon the occurrence of mechanical shock, and C_{12} discharges through R_{20} and V_4 until its potential is reduced to about 30 volts. V_3 however gets its anode potential from

the charge on C_{12} , and when that potential is less than about 70 volts, V_3 cannot produce sufficient signal to fire V_5 . Firing of V_4 therefore serves to limit the signal applied to the grid of V_5 to a value insufficient to fire it. This action takes place almost instantly, and owing to the time constant of C_{12} — R_{21} it takes about one second to recharge C_{12} to the 70 volts necessary to reignite V_3 . During that period V_5 cannot be fired. When therefore a microphonic signal is generated in the circuit because of mechanical shock, the firing potential applied to the grid of V_5 in response to that signal is delayed, and in the meantime the shock produces a train of electrical events which inhibit firing of V_5 . In colloquial terms the "countermine" action of S_2 , V_4 and C_{12} "gets there first."

The broken line of Fig. 5 shows the effect on the voltage of point b of the countermine action of V_4 , and Fig. 7 shows that with the countermine action, V_5 does not attain its critical firing voltage.

There has thus been described a circuit in which a gas tube is fired at the end of a predetermined period of delay in response to firing of a second gas tube which is in turn ignited by signals generated within the system of which the circuit forms part. If these signals are caused by mechanical shock, a third gas tube is fired substantially instantaneously in response to and upon occurrence of the shock, and this reduces the anode potential of the second gas tube to such a point that it cannot provide sufficient signal to fire the gas tube first mentioned.

We claim as our invention:

1. In a device which includes a gas tube, the combination with said tube of a second gas tube provided with an anode, a source of potential for said anode constituted by a source of direct current having a capacitor shunted thereacross; one terminal of said capacitor being connected to said anode, a time delay combination connecting said anode and said first mentioned tube, signal-responsive means for firing said second tube, a third gas tube connected across said capacitor, and means substantially instantaneously responsive to mechanical shock to elements of said device for firing said third tube whereby to discharge said capacitor and thereby to prevent the potential of said anode from rising to a value sufficient to fire said first tube in response to false firing of said second tube as a result of mechanical shock.

2. A combination according to claim 1 wherein the means for firing said third tube include a normally closed switch adapted to be opened substantially instantaneously in response to mechanical shock thereto, and connections for applying a transient pulse of energy to said third tube in response to opening of said switch.

3. In a control circuit, a first gas tube, means for normally firing said first tube at the end of a predetermined period of delay in response to the firing of a second gas tube, means for firing said second gas tube in response to signals generated within a system of which said circuit forms a part, a third gas tube adapted, when fired, to prevent normal firing of said first gas tube in response to the firing of said second gas tube, and means including an element actuatable by a mechanical shock to cause said third gas tube to fire before the end of said period of delay, in response to a mechanical shock of sufficient magnitude to actuate said element.

4. In a control circuit, a first gas tube having a control electrode, means for normally applying to said control electrode after a predetermined delay period a potential of sufficient magnitude to fire said tube in response to the firing of a second gas tube, means for firing said second gas tube in response to signals generated within a system of which said circuit forms a part, a third gas tube adapted, when fired, to prevent the application of said potential to said control electrode, and means actuatable by a mechanical shock of sufficient

magnitude to cause spurious signals to be generated within said system to cause said third gas tube to fire before the end of said delay period.
